[57] **CLAIM**

The ornamental design for a tub or the like, as shown and described.

DESCRIPTION

FIG. 1 is a perspective view taken from the top, rear and left side of a tub or the like showing our new design; FIG. 2 is a top plan view thereof;

FIG. 3 is a cross-sectional view taken on line 3—3 of FIG. 2;

FIG. 4 is a cross-sectional view taken on line 4—4 of FIG. 2;

FIG. 5 is a cross-sectional view taken on line 5—5 of FIG. 2; and

FIG. 6 is a cross-sectional view taken on line 6—6 of FIG. 2.

The fragmentary broken line representations of the deck in FIG. 1 and of holes in FIGS. 1-3 are for the purpose of illustration only.
